CONSTRUCTIONAL ELEMENTS AND METHOD OF PRESTRESSING SAME

George Mountford Adie, 7 Carlos Place,
London, England

Continuation of application Ser. No. 239,553, Nov. 23,
1962. This application July 12, 1966, Ser. No. 564,626
6 Claims. (Cl. 52—223)

This application is a continuation of my U.S. application 239,553, filed Nov. 23, 1962, now abandoned.

This invention relates to constructional elements for use in buildings and the like. It is applicable to elements in the form of slabs, planks and the like comprising at least two sheets, at least one of which is formed with a regular series of either dimples or channels the apices of the dimples or the bottoms of the channels being secured to an adjacent sheet. Such an element will be hereafter referred to as an "element of the type described."

The invention is concerned with the deliberate pre-stressing of such an element. This is done in accordance with the invention by subjecting at least one of the sheets of the element to an applied force to stress the sheet either before or after it is secured to the other sheets of the element. If the stressing is carried out before fastening the sheet to the element the stress is preferably caused by subjecting the sheet to an applied force in the plane of the sheet and then securing the stressed sheet to an unstressed sheet or oppositely stressed sheet of the element by fastening the apices of the dimples or the bottom of the channels of one of the sheets to the other sheet and then releasing the force applied to the first sheet. Due to the various points of connection between the sheets, the previously stressed sheet or sheets cannot return to their original unstressed condition without distorting the sheet to which they are fastened. The construction of the sheets is made such that distortion is controlled and all sheets then become stressed. If the element consists only of two sheets the first sheet remains stressed in the original sense (tension or compression) but to a lower degree, and the second sheet which was previously unstressed, is stressed in the reverse sense.

One method of stressing a preformed element is to cast a layer of concrete or other suitable material on to the uppermost sheet of the element the concrete being pre- or post-tensioned by means of wires, the stress being transferred to the uppermost sheet and thence to the other sheets.

A further way of stressing the element is to connect bars rods, strips or the like which are stressed by an applied force either in tension or in compression, at released places, on a side of a preformed element and then releasing the applied force.

If a dimpled sheet is stressed in tension and then secured to a second dimpled sheet, the apices of the dimples being fastened together, the applied force being then released, the first sheet loses half its tension which appears as compression in the second sheet. Such an element is stronger than an unstressed element. If the element or slab is positioned so that the sheet in tension is uppermost, and the sheet in compression is lowermost, then it will be capable of spanning further distances for a given quantity of material, or of carrying heavier loads for a given span compared with a similar unstressed slab. For example, the

2

slab can be used as permanent shuttering to support wet concrete over a longer span than an unstressed slab without propping, or alternatively the element can be used vertically for other load bearing requirements.

5 If desired the sheets can be stressed in one or more directions for example two directions at right angles in the plane of the sheet. For a rectangular sheet for example stress can be applied in the direction of both pairs of opposite sides giving additional strength to slabs which in use can be supported at all four sides and for a hexagonal sheet stress can be applied at three pairs of opposite sides.

Both the sheets may be dimpled in which case the sheets may be joined either by fastening the apices of the dimples of the two sheets together or by securing the apices of the dimples of one sheet to the flat lands present between the dimples of the other sheet. In the latter case the forces are transferred direct from the dimples of one sheet to the flat lands in the plane of the sheet. In the case where the slab comprises a dimpled sheet and a plane sheet either 15 the dimpled sheet or the plane sheet may be initially tensioned. For convenience it may be preferable to tension the plane sheet and to fasten an unstressed dimpled sheet to it.

The dimples may have any convenient regular outline 20 such for example as hemispherical, conical, pyramidal or parabolic and they may have any convenient cross sectional shape such for example as circular, triangular, square, hexagonal or any other regular polygonal shape. The dimples are conveniently, but not necessarily, truncated so that those on one sheet can be more firmly fastened to those of the other sheet. The dimples of one sheet 25 may be deeper than those of another sheet.

The sheets may be made of any suitable material such 30 for example as metal, e.g., steel or aluminium, plastic or pressed fibre and the method used for securing the sheets together will depend upon the material of those sheets. For example, if both sheets are of metal or plastic they may be fastened together by welding or by adhesive, if either or both of the sheets are of pressed fibre they may 35 be riveted together.

For some uses it is desirable for one of the sheets to be 40 of one material say one particularly suited for being stressed in compression, and the other of another material, say one particularly suited for being stressed in tension. Furthermore the thickness and quality of the two 45 sheets can be different if required.

The two stressed sheets may comprise part of a composite slab in which the initially stressed sheets are secured to other plane or dimpled sheets.

50 Not all the dimples of the two sheets need to be joined together for all purposes.

If desired, the element can be stressed when arched giving a "convex shape in tension." This form is suitable for some specialised purposes such as for example a floor slab.

55 In a multisheet slab that side which has been stressed for tension will be placed uppermost and that side which has been stressed for compression downwards. Thus, the concrete is placed on the uppermost side and the tension will serve to support the wet concrete which would otherwise cause compression of the top sheet. Placed thus the stressed element can support a great weight of concrete.

60 It will be realized that alternatively the compressive force can be applied to the slab if required, whilst it is being made instead of, or as well as, a tensile force.

Various embodiments of constructional elements and methods of prestressing the elements in accordance with the invention will now be described with reference to the accompanying drawings in which:

FIGURE 1 is an isometric view of part of a sheet for an element in accordance with the invention;

FIGURE 2 is a cross-section through one form of slab comprising two of the sheets illustrated in FIGURE 1;

FIGURE 3 is a cross section of yet a further form of slab;

FIGURE 4 is a diagram illustrating the method of stressing a slab in situ;

FIGURE 5 is a cross section of a slab having a plane centre sheet;

FIGURE 6 is a fragmentary plan view of a slab stressed by means of rods applied to its upper surface, and

FIGURE 7 is a section diagrammatically illustrating a four sheet slab.

The sheet shown in FIGURE 1 has a regular series of conical dimples 2 formed therein, the apices 4 of the cones being truncated. The dimples are arranged on the sheet in parallel rows and on a rectangular grid so that a series of passageways, indicated by dot and dash lines 6—6 is formed by the lands 8 between the dimples. These passageways extend across the sheet and are arranged on a rectangular grid.

One of the sheets shown in FIGURE 1 is gripped along the entire length of each of a pair of opposite sides by flat steel jaws or vises. These jaws, which have to be capable of exerting pressure, are then pulled in opposite directions by hydraulic or other means, so as to stress the sheet to any desired figure, say 20,000 pounds. This has the effect of slightly elongating the length of the dimpled sheet, and if this is say from 10 to 20 feet long the elongation may be of the order of $\frac{1}{4}$ " depending upon the material of the sheet. This sheet will then be stressed by forces of up to 20,000 pounds.

A second sheet similar to that shown in FIGURE 1, but which is unstressed, is then placed on the first sheet with the truncated dimples of the two sheets abutting as can be seen in FIGURE 2. In practice these truncated faces may be slightly offset from each other by, in this example, a maximum of an $\frac{1}{8}$ ", but an adequate overlap is still provided (the figures do not show the overlap, as they only illustrate a very short length of the slab). The truncated faces of the pyramidal dimples of the two sheets are then secured together by welding, or by rivets 10 or by other means, whilst the stressed sheet remains under load. The total area of the welds or the number, side and disposition of the rivets, is arranged so as to resist the forces which result when the jaws are released and the forces which will be caused later when the element is subjected to its designed load. The pressure between the jaws is then released and immediately the stressed sheet seeks to return to its former shape and size, but this is resisted through the connections to the unstressed sheet. A system of forces is then set up which may be considered as being a "closed system operating in the slab" and the tension in the initially stressed sheet diminishes to the point at which it is balanced by a corresponding compression in the second sheet.

When the element is positioned so that the sheet in tension is uppermost, and the sheet in compression is lowermost, it is much stronger than it would be were it to be unstressed and can carry greater loads and/or span longer distances. This can result in the saving of steel or other structural material.

The means for tensioning or compressing the first sheet need not be continuous along an edge and a number or the like (for tensioning) can be used, each applying a different force to the sheet so that the stress pattern can be adjusted and the tendency to distort controlled or a desired distortion produced.

In the construction shown in FIGURE 3 the upper sheet, generally indicated at 14, which is of the same gen-

eral design as that shown in FIGURE 1, is secured to an identical lower sheet, generally indicated at 16 by securing the truncated apices of the conical dimples together. A layer of concrete 18 is then cast on to the sheet 14, which concrete is either pre- or post-stressed by means of wires 20 passing through it. The stressed concrete subjects the sheet 14 to stress and stress is also transferred from the sheet 14 to the sheet 16. Hence the element (including the concrete layer) becomes prestressed.

Stressing may be carried out on a building site by, for example, welding or otherwise joining a sheet 26 (see FIGURE 4) which is formed with dimples arranged as on the sheet shown in FIGURE 1, but with the dimples extending upwards to an existing part of a building structure, diagrammatically shown at 24, which may be in the process of construction, and then applying a stressing force to another sheet 26 of the slab, and securing the stress sheet, whilst it is subjected to the applied force, to the first sheet, and also if desired to the building structure. On release of the applied force, the slab will become stressed in the desired manner. It will be appreciated that this stress can be achieved by performing the operation in a different sequence.

FIGURE 5 illustrates a construction in which a stressed dimpled sheet 28 is secured to an initially unstressed sheet 30 through a centre plane sheet 32. Alternatively the plane sheet may be stressed and secured to two unstressed dimpled sheets and/or the plane sheet can be arranged at one or both sides of the two dimpled sheets.

FIGURE 7 illustrates a slab produced by a further pre-stressing method wherein bars or rods 34 are subjected to an applied force (either tensile or compressive) and then secured to the upper face of a dimpled sheet 36, which is the outer sheet of a multisheet slab. On releasing the applied force, the stress in the rods is transmitted via the points of connection, to the sheet 36 and to the other sheets of the slab so that a closed and balanced stress system is set up within the slab.

An element prestressed in accordance with the invention can comprise any desired number of dimpled sheets fastened either directly together, or with the interpositioning of plane sheets. FIGURE 8 illustrates a form sheet slab, the upper or two upper sheets being stressed in either tension or compression and the lower or two lower sheets in compression or tension respectively.

If dimpled sheets are employed for the slab, the slab will have passages or paths running through it in two or more directions along the lines 6 depending upon the arrangement of the dimples, which passages can be used to carry pipes, wires and the like.

The invention is applicable not only to a method of prestressing a slab, plank or like element, but also to the element when stressed.

I claim:

1. A method of prestressing a constructional element having at least two sheets, at least one of which sheets is formed with a regular series of dimples, the said method comprising subjecting at least one of the sheets of the element to a tensional force in its plane flat condition to stress the sheet, securing the stressed sheet to another sheet of the element and then releasing the tensional force.

2. A method as claimed in claim 1 in which the said one sheet is stressed in more than one direction.

3. A method as claimed in claim 1 in which the element includes a flat sheet.

4. A method as claimed in claim 1 in which all the sheets are dimpled the apices of the dimples of the said stressed sheet being secured to the apices of the dimples of the said other sheet of the element.

5. A method of prestressing a constructional element having at least two sheets, at least one of which is formed with regular series of dimples, the said method comprising subjecting at least one of the sheets of the element to a compressive force in its plane flat condition to stress

the sheet before it is secured to the sheets of the element, securing it to the said other sheets, and then releasing the applied force, and in which the element includes a flat center sheet which is subjected to an applied compressive force before and while it is secured to the relatively outer sheet of the element.

6. A prestressed constructional element having at least two sheets secured together, at least one of said sheets being formed with a regular series of dimples, one of the sheets of the element supporting a layer of concrete containing stressed wires.
